UNITED STATES PATENT OFFICE.

HENRY FORD, OF DEARBORN, MICHIGAN.

MANIFOLD CONSTRUCTION FOR INTERNAL-COMBUSTION ENGINES.

Original application filed August 2, 1920, Serial No. 400,638. Divided and this application filed September 21, 1922. Serial No. 589,536.

- This invention relates to improvements in manifold construction for internal combustion engines, being a division of the application filed by me August 2, 1920, Serial 5 No. 400,638.
- While the present invention is applicable for use in connection with engines of a general type, it is particularly adapted for use with the engine more particularly described in the said parent application, wherein two circular series of cylinders are arranged side by side, with the cylinders of a series symmetrically disposed relative to vertical and horizontal planes which extend 10 through the crank shaft axis with the planes extending in the direction of length of such axis, the cylinders being arranged in such manner as to locate a pair of cylinders above and a pair of cylinders below 15 the horizontal plane and a pair on each side of the vertical plane, the cylinders being preferably arranged at angles to such planes in such manner as to practically bisect the angles between the planes.
- The manifold construction employed 20 with an engine of this type is designed to serve similarly positioned pairs of the cylinders of both series, the manifold structures being duplicated for the second pairs.
- In the embodiment illustrated herein, the 25 manifold structure for a set of pairs is shown as located to serve the cylinders on one side of the vertical plane, the structure being mounted between the upper and lower cylinders of such pairs, thus serving one-half of the cylinders of the engine. It will be obvious, of course, that, so far as the 30 present invention is concerned, the manifold structure or formation may be applied so as to serve the cylinders at one side of the horizontal plane, thus placing it between the upper pairs of the two series.
- The invention has for its general object 35 the provision of a manifold structure or formation of a simple type readily produced and installed, and which is effective to provide a structure of high efficiency.
- Another object is to provide a formation 40 of this type in which the several cylinders served by the formation will be properly served, and at the same time provide an arrangement by which the distance traveled by the fuel—in connection with the intake—or the exhaust gases—in connection with the 45 exhaust—will be substantially the same in connection with each of the cylinders served by the formation. That is, the distance traveled by the fuel from the intake portion of the manifold to the cylinder will be substantially the same for each of the 50 cylinders served by the formation; this is true also with respect to the distance traveled by the exhaust gases. However, the distance traveled by the fuel may vary from that traveled by the exhaust gases, 55 the drawings showing this distance, as practically the same.
- To these and other ends, therefore, the nature of which will be readily understood as the invention is hereinafter disclosed, 60 said invention consists in the improved construction and combination of parts, hereinafter more fully described, illustrated in the accompanying drawings, and more particularly pointed out in the appended 65 claims.
- In the accompanying drawings, in which similar reference characters indicate similar parts in each of the views,
- Figure 1 is a detail sectional view taken 70 through one of the manifold structures or formations, illustrating the manner in which the inlet and exhaust conduits are connected up with the pairs of cylinders served by the formation.
- Fig. 2 is a sectional view taken on the line 2—2 of Fig. 1.
- Fig. 3 is a view of the structure of Fig. 2, the view being in end elevation and looking toward the right in Fig. 2.
- Fig. 4 is a view showing a pair of manifold formations mounted in proper position relative to an engine structure such as is disclosed in the parent application, the engine being shown in outline and without the operating parts, the view being designed to illustrate the manner in which the manifold structure is mounted, the view showing the manifold structure in section taken on lines substantially at right angles 80 to the section shown in Fig. 1.
- Referring first to Fig. 4, 26 designates a cylinder having a head portion 28 extended laterally to provide an enlarged portion 28^a into which the connections from the manifold are designed to deliver a charge for the cylinder, and from which connections deliver the exhaust gases from the cylinder to the exhaust portion of the manifold, the control to these connections being provided by 85
- 100
- 105
- 110

inlet and exhaust valves of suitable type and which control the entrance to or discharge from the enlarged portion of the head. Each head is provided with a channel 28^b for the 5 intake and a channel 28^c for the exhaust, these channels extending generally, in the embodiment shown, in a vertical direction, the inner ends being arranged to carry these to the plane of the outer ends of the cylinder 10 body, the particular arrangement shown in the parent application setting up a curved inner end to the channel, thus permitting the valve seats to be so located as to permit the valves to operate in directions such as 15 not to effect the manifold formation.

By extending channels 28^b and 28^c in a general vertical direction, with the outer ends of these channels facing each other from an upper and a lower cylinder respectively, it is 20 possible to mount a manifold structure or formation intermediate such channel ends, thus making it possible to use a single manifold structure from the four cylinders located at one side of a vertical plane extending 25 through the crank shaft axis.

As shown in Fig. 4, the manifold structures are substantially duplicates.

The particularly embodiment of manifold used for the purpose of illustrating the invention is shown as in the form of a casting 46 (Fig. 2) provided with an exhaust chamber 47 and an intake chamber 48, the latter having a suitable passageway 48^a leading thereto and which is connected up with 30 the carburetor structure or structures, the exhaust chamber having an outlet 47^a leading to a suitable point, such for instance as a muffler, not shown. As shown in Figs. 1, 2 and 3, the major portion of the walls of 35 chamber 48 are exposed within chamber 47 so that the walls of the intake chamber are practically bathed with the exhaust gases, thus primarily heating the intake prior to the delivery of the charge to the cylinder.

Fig. 1 shows the manner in which the manifold can be connected up to the lateral extension 28^a of head 28, it being seen that intake channels 28^b are the intermediate channels leading into chamber 48 by the 40 connections 49, the exhaust channels 28^c being the outer channels and leading into chamber 47, similar connections 49 being provided.

As will be seen, all of the intakes for the 45 four cylinders are of substantially the same length as are the exhaust connections, so that there is practically a uniformity within the manifold, this latter being especially true in connection with the particular type of engine being served in which the firing sequence is such as to set up conditions of general uniformity within both the intake and the exhaust portions of the manifold.

It will be seen, from Figs. 1 and 4, that 50 the exhaust from one pair of cylinders is de-

livered into the manifold in direction opposite that of the other pair of cylinders being served by the manifold. The possibility of the exhaust gases from one cylinder being delivered into the connections from the cylinder on the opposite side of the horizontal plane is avoided by arranging the connections in such manner that the opposing exhaust connections are offset relative to each other, so that the delivery ends of these connections face a wall of the manifold. While the same difficulty is not present with respect to the intake, the same general offset arrangement is employed, so that the service connections for each cylinder are properly 55 and symmetrically arranged with respect to the cylinder formation, the structure, at the same time, providing for this general equality in distance traveled by the fuel or the gases.

As will be seen, the arrangement is one of simplicity, connections 49 being similar, the casting 46 being the more or less special construction of the formation. Since the connections are connected up to the manifold by suitable and well known structures such as glands, it will be readily understood that the casting can be readily fashioned, the complete formation being readily assembled to produce the tight joint effect that is desirable with this type of apparatus.

While I have herein shown and described an illustrative embodiment of the present invention and in its preferred form, it will be readily understood that changes and modifications therein may be found desirable or essential in meeting the various exigencies of use or of installation, and I desire to be understood as reserving the right to make any and all such changes and modifications 100 as may be found desirable or necessary in so far as the same may fall within the spirit or scope of the invention as expressed in the accompanying claims when broadly construed.

Having thus described my invention, what I claim as new is:

1. A manifold structure adapted for internal combustion motors wherein the cylinders served by the structure are spaced apart with the manifold structure located therebetween, a casing having an intake chamber and an exhaust chamber elongated in the direction of length of the casing and of the crank shaft of the motor, an admission port for the intake chamber and an outlet port for the exhaust chamber, said chambers and ports being permanently positioned relatively one to the other with the chamber and its corresponding port in permanently open communication, said casing also carrying service ports leading in opposite directions from and in directions lateral of the direction of length of said chamber and adapted to be connected in permanently-open communica-

cation with the corresponding ports of the cylinders being served, the service ports being located intermediate the ends of the chamber and arranged in a succession in which the intake and exhaust ports for a cylinder are located side by side to permit symmetrical connection of service connections between the ports and cylinder with the connections extending in substantial parallelism.

2. A manifold structure adapted for internal combustion motors wherein the cylinders served by the structure are spaced apart with the manifold structure located therebetween, a casing having an intake chamber and an exhaust chamber elongated in the direction of length of the casing and of the crank shaft of the motor, an admission port for the intake chamber and an outlet port for the exhaust chamber, said chambers and ports being permanently positioned relatively one to the other with the chamber and its corresponding port in permanently open communication, said casing also carrying service ports leading in opposite directions from and in directions lateral of the direction of length of said chamber and adapted to be connected in permanently-open communication with the corresponding ports of the cylinders being served, the axes of said service ports lying in the same plane, with the ports on one side offset with respect to the ports of the opposite side, the service ports being located intermediate the ends of the chamber and arranged in a succession in which the intake and exhaust ports for a cylinder are located side by side to permit symmetrical connection of service connec-

tions between the ports and cylinder with the connections extending in substantial parallelism.

3. A manifold structure adapted for internal combustion motors wherein the cylinders served by the structure are spaced apart with the manifold structure located therebetween, a casing having an intake chamber and an exhaust chamber elongated in the direction of length of the casing and of the crank shaft of the motor, an admission port for the intake chamber and an outlet port for the exhaust chamber, said chambers and ports being permanently positioned relatively one to the other with the chamber and its corresponding port in permanently open communication, said casing also carrying service ports leading in opposite directions from and in directions lateral of the direction of length of said chamber and adapted to be connected in permanently-open communication with the corresponding ports of the cylinders being served, the axes of said service ports lying in the same plane, with the ports on one side offset with respect to the ports of the opposite side, the service ports being located intermediate the ends of the chamber and arranged in a succession in which the intake and exhaust ports for a cylinder are located side by side to permit symmetrical connection of service connections between the ports and cylinder with the connections extending in substantial parallelism.

In testimony whereof I affix my signature.
HENRY FORD.
